UNITED STATES PATENT OFFICE.

WILBUR L. WRIGHT, OF BALTIMORE, MARYLAND, ASSIGNOR TO THE PAPER VESSELS COMPANY, OF BALTIMORE, MARYLAND, A CORPORATION OF MARYLAND.

PAPER CONTAINER.

1,188,526.

Specification of Letters Patent. Patented June 27, 1916.

Application filed February 28, 1916. Serial No. 80,870.

To all whom it may concern:

Be it known that I, WILBUR L. WRIGHT, a citizen of the United States, and resident of Baltimore, State of Maryland, have invented certain new and useful Improvements in and Relating to Paper Containers, of which the following is a specification.

This invention relates to certain improvements in paper containers; and the objects and nature of the invention will be readily understood by those skilled in the art in the light of the following explanation of the accompanying drawings illustrating what I now believe to be the preferred mechanical expression or embodiment of my invention from among other forms and constructions within the spirit and scope thereof.

In the manufacture of so-called liquid tight paper containers it has heretofore been exceedingly difficult, if not impossible, to produce paper containers that would hold liquids for any reasonable length of time without leakage and that were of such formation and construction as to be capable of economical manufacture to permit sale thereof at a low price.

It is the object of my invention to produce a paper container of such construction and formation as to render the same liquid tight and capable of holding liquids for reasonable lengths of time without leakage and which can be manufactured at low cost.

The invention consists in certain novel features in construction and in combinations and arrangements as more fully and particularly set forth and specified hereinafter.

Referring to the accompanying drawings:—Figure 1, is a perspective view of the bottom portion of an inverted paper container, constructed in accordance with my invention. Fig. 2, is a vertical section showing the container bottom as it appears before the crimping or spinning operation. Fig. 3, is a longitudinal section. Fig. 4, is a detail section on an enlarged scale.

The cylindrical paper body 1, of the container is usually formed by strips of paper spirally wound on a tube winder and suitably secured, as will be readily understood by those skilled in the art, although my invention is not limited to spirally wound

paper container bodies. This body is formed with an end closure consisting of a flat inner sealing disk of relatively large diameter and an outer flanged cap or disk 3, formed with an annular flange 4, and a peculiar crimped or spun end or bead forming an end rim of the container and locking the flanged disk in the container end to resist pressure in either direction longitudinally of the container body.

The diameter of the sealing disk 2, is greater than the diameter of the container body and said disk is paraffined or otherwise waterproofed before being inserted in the container body. In fact, the container body and the flanged disk or cap are preferably both paraffined or otherwise suitably waterproofed before the parts are assembled. The inner sealing disk is preferably thoroughly waterproofed throughout its peripheral edge as well as its side faces and waterproofing material of an adhesive nature such as paraffin is preferably employed for this purpose.

In assembling the parts, the cylindrical body 1, is usually placed on a mandrel having a flat upper end, with the upper end of the body projecting a distance above the mandrel, the inner sealing disk 2, is then inserted in the projecting upper end of the body. This cap is usually inserted in an edgewise or inclined position, because of its large diameter, and then so far as possible by hand, is pressed into approximately a horizontal position on the upper end of the mandrel. The flanged cap or disk 3, is then inserted in the upper end of the body in an inverted position with its flange projecting upwardly and is pressed down on the inner sealing disk and toward the mandrel end, see Fig. 2. The body is so arranged on the mandrel, that when the flanged disk is inserted and pressed down approximately into position for crimping, its flange will be approximately cylindrical and tightly fitting the inner surface of the body end, with the body end 6, projecting upwardly an approximately predetermined distance beyond the edge of the flange. A suitable rotary crimping or spinning and presser head is moved toward the body end and the disk therein to fold the body end 6, inwardly over the end edge of the flange 4, of the outer disk or cap and then downwardly and tightly against

100

110

the inner face or circumference of said flange and the end edge of the body end tightly abutting the outer or upper side face of the disk or cap 3.

- 5 The longitudinal movement of the spinning head toward the end closures or disks 2, 3, is sufficient to tightly turn or double the outer end portion 7, of the flange 4, inwardly and back toward the disk 3, and to buckle and crease said flange, and also to buckle the inturned portion 8, of the body end and crease the same radially and outwardly to interlock with the flange 4, and fit behind the double end 7, thereof, and to operate therewith in forming a lock. The spinning head is thus crushing or creasing the flange 4, and the body end 8, compresses said portion 8, against the outer face of disk 3, and at the same time said head compresses the inner and outer disks toward the mandrel end and flattens the same thereagainst and presses the adjoining faces of said disks so tightly together that they are caused to adhere particularly by reason of the waterproofing material thereon.

The action of the spinning head tends to tightly draw the outer portion of the body end 6, longitudinally and form the same with a smooth non-creased surface at the same time that the disks 2 and 3, are being flattened out against the mandrel end so that the peripheral edge of the enlarged inner disk 2, is approximately driven radially into the wall of the body to form a decided positive exterior annular enlargement, rib or bulge 9, and a corresponding inner groove or seat, while the radial or outward pressure on the rounded annular edge of the mandrel and corner of the flange cap 3, cause the peripheral edge 10, of the inner sealing disk to flare or flatten in the annular groove in the body wall to form and constitute a liquid tight joint between said disk and the body wall. The formation of this liquid tight joint is aided by the welding or adherence of the waterproofing material therein and thereon into and with the surface of the body wall and the waterproofing material therein and thereon. This joint can also be strengthened by application of paraffin or other waterproofing to the interior of the container after the completion of the end closure.

In the completed end closure, the inner sealing disk 2, is braced and strengthened to resist loosening or bulging under internal pressure, while the outer disk is braced against such pressure by the peculiar lock formed by the longitudinally compressed and upset crimped flange and wall end. The inner sealing disk is protected against outward pressure by the outer or flanged disk which is also braced against such pressure by the interlocking formation of the body wall end and disk flange. This end closure can

be formed economically and at low manufacturing cost and provides a liquid tight container body that not only greatly increases the strength and stiffness of the container but enables the same to hold liquids for long periods of time without leakage or disintegration of the closure.

If so desired, the container can be provided with a top or cover 12, having an end closure of the same formation and structure as described and forming the container bottom, although my invention is not so limited.

It is evident that various changes and modifications might be resorted to without departing from the spirit and scope of my invention and hence I do not wish to limit the invention to the exact disclosure hereof.

What I claim is:—

1. A paper material container having an end closure consisting of an inner sealing disk and an outer flanged disk arranged within the container body, the end of said body spun or crimped inwardly over the flange of said flanged disk to form a crimp locking said flanged disk in the body end, said disks being flat and parallel and held in engagement bracing each other against dishing and displacement.

2. A paper container having a liquid tight end closure consisting of a large diameter inner sealing disk forced into the container body and forming an annular bulge in said body, the annular edge of said disk being seated and sealed in said bulge and a flanged outer disk in the container body and fitted against said sealing disk, the end of the body being tightly spun and crimped around and to the flange of said outer disk to fixedly lock the same in position backing and bracing said sealing disk.

3. A paper container having a body, a flat inner sealing disk having its annular edge compressed into and tightly fitting in an annular outward bulge in said body, and a flat outer disk seated against and backing said inner disk and formed with an annular outwardly extending flange within the body, the end of the body being tightly crimped inwardly around said flange and in connection therewith forming a compressed locking bead.

4. A paper container having a body formed with an annular internal depression, a relatively large diameter flat inner sealing disk spanning said body and having a flared annular edge seated in said depression and providing a liquid tight joint between the disk and wall of the body, and a flanged outer disk spanning the interior of the body and fitting and stiffening said inner disk against loosening and dishing and having its flange and the end of the body united by a crimped bead to form a lock.

5. A paper container having its body provided with and spanned by a flat inner seal-

ing disk having its annular edge pressed into and sealed to the surrounding wall of the disk to form a liquid tight joint maintaining the disk against longitudinal movement in 5 the body, said body being also provided with and spanned by a flanged outer sealing disk fitting said inner disk and united thereto by waterproofing material, the flange of said disk and the end wall of the body being 10 tightly locked together by a permanent crimped bead forming the annular end rim of the container.

6. A paper container having an end closure consisting of a flat inner sealing disk of enlarged diameter held in the container 15 body under pressure and spanning the interior of said body with its annular edge wedged against and distorting the surrounding wall of said body and united thereto by a liquid tight joint, and a flat outer cap 20 pressed against said inner cap and having an annular flange within said body and permanently locked therein by a compressed crimped bead tightly fitting the outer face 25 of said outer disk and formed by the end wall of the body and said flange.

WILBUR L. WRIGHT.
